(57) **CLAIM**

The ornamental design for a dock ladder, as shown and described.

DESCRIPTION

FIG. 1 is a top right side perspective view of a dock ladder showing a new design in a first position where the dock ladder can extend downward from a dock when the dock ladder is attached to the dock;

FIG. 2 is a front side plan view of the dock ladder in the first position as shown in FIG. 1;

FIG. 3 is a rear side plan view of the dock ladder in the first position as shown in FIG. 1;

FIG. 4 is a left side plan view of the dock ladder in the first position as shown in FIG. 1;

FIG. 5 is a right side plan view of the dock ladder in the first position as shown in FIG. 1;

FIG. 6 is a top plan view of the dock ladder in the first position as shown in FIG. 1;

FIG. 7 is a bottom plan view of the dock ladder in the first position as shown in FIG. 1;

FIG. 8 is a top right perspective view of the dock ladder as shown in FIG. 1 in the first position where the dock ladder extends downward from a deck of a dock, shown in dash broken lines, when the dock ladder is attached to the dock; and

FIG. 9 is a top right perspective view of the dock ladder as shown in FIG. 8 in a second position where the dock ladder extends upward from the deck of the dock, shown in dash broken lines;

FIG. 10 is a top right side perspective view of another dock ladder showing a new design in a first position where the dock ladder can extend downward from a dock when the dock ladder is attached to the dock;

FIG. 11 is a front side plan view of the dock ladder in the first position as shown in FIG. 10;

FIG. 12 is a rear side plan view of the dock ladder in the first position as shown in FIG. 10;

(Continued)

FIG. 13 is a left side plan view of the dock ladder in the first position as shown in FIG. 10;
 FIG. 14 is a right side plan view the dock ladder in the first position as shown in FIG. 10;
 FIG. 15 is a top plan view of the dock ladder in the first position as shown in FIG. 10; and,
 FIG. 16 is a bottom plan view of the dock ladder in the first position as shown in FIG. 10.
 In the drawings, the dash broken lines are for the purpose of illustrating environment only and form no part of the claimed design.
